UNITED STATES PATENT OFFICE.

LOGAN CORNELIUS, OF HARDY, OKLAHOMA.

FENCEPOST.

1,336,680.

Specification of Letters Patent. Patented Apr. 13, 1920.

Application filed June 23, 1919. Serial No. 306,041.

To all whom it may concern:

Be it known that I, LOGAN CORNELIUS, a citizen of the United States, residing at Hardy, in the county of Kay and State of Oklahoma, have invented a new and useful Fencepost, of which the following is a specification.

This invention relates to fence posts, the primary object being to provide a fence post particularly adapted to lands which are subjected to floods and which is of such a construction as to permit the posts carrying the fence wires to assume a horizontal position to allow driftwood and the like to pass thereover without damaging the fence construction or posts, the fence posts being manually raised to operative position after the water has passed from the land.

A further object of the invention is to provide a fence post which will automatically assume a horizontal position upon the engaging of the fence post by floating objects coming into contact therewith, to allow these objects to float over the fence without damaging the same.

It is another object of this invention to provide a fence post having the above characteristics, having a latch mechanism associated therewith for retaining a gate in closed position which is automatically released to allow the fence post and fence to fall to the ground but which will leave the gate standing in operative position.

Still another object resides in the provision of a fence post and fence construction that is rigidly retained in vertical position but which will be readily released to allow the fence post to assume a horizontal position upon the ground upon the proper pressure being exerted against the fence post or fence.

Another object of this invention resides in a fence post which will readily swing to a horizontal position when the land becomes flooded and which will be of such a construction as to permit the post being raised to its normal position without the use of tools and the re-arranging of the fence.

An additional object of this invention resides in the provision of a fence post having the above characteristics which is simple in construction, which consists of few parts that may be readily assembled and disassembled, and which may be manufactured and sold at a nominal cost.

With the above and other objects and ad-

vantages in mind, the invention consists of combinations of elements, constructions and arrangements, operations and general assemblage, the details of which will be hereinafter referred to and claimed, the invention being illustrated in the accompanying drawings, wherein:

Figure 1 is a side elevation of a fence post constructed in accordance with my invention;

Fig. 2 is a like elevation taken at right-angles to Fig. 1;

Fig. 3 is a transverse sectional view through the post showing the manner of connecting the two sections of the post together;

Fig. 4 is fragmentary side elevation of a modified form of the post;

Fig. 5 is an elevation taken at right-angles to Fig. 4; and

Fig. 6 is a top elevation of the construction shown in Figs. 4 and 5.

On the drawings, wherein like characters of reference designate like parts in all of the views, the numeral 5 designates the stationary section of my improved fence post which is embedded in the ground or positioned in a cement foundation of usual construction. The upper end of the stationary section 5 has lugs 6 formed upon one face thereof of triangular formation in cross section and arranged at right-angles to each other. A movable section of the post indicated at 7 is provided with recesses 8 which normally receive the lugs 6. The upper end of this section 7 is provided with a recess 9 of V-shaped formation which receives a lug 10 identical with the lugs 6 of the main section of the post, the latter being indicated at 11 and being pivotally connected with the upper end of the section 7 by a pivot bolt 12 which extends at right-angles to the pivot bolt so that the main section 11 may swing at right-angles to the section 7, the wires of the fence being attached to this main section 11.

Pivotedly mounted upon one face of the stationary section 5 and adapted to swing in the same plane as the section 11 is a locking plate 13 the outer face of which is beveled toward one of its longitudinal edges. This plate is provided with a slot 14 which extends transversely of the plate and receives the bolt 7'. A finger is formed at the upper end of the wedge or locking plate and is designated by the numeral 15'.

The upper end of the movable section 7 is cut out from one side thereof as indicated at 16 to permit the lateral or swinging movement of the main section of the post. Extending transversely through and projecting from one side of the section 11 is a rod 17 and encircling this rod is an expansible coil spring 18. A trip bar 20 extends forwardly and angularly from the section 11 and is hingedly connected with this section at its lower end as indicated at 21. This bar is provided with a transverse opening 22 intermediate its ends in which is engaged the rod 17, the expansible 15 coil spring bearing against this bar 20 and urging the same forwardly. Fixed to rotate within pintles or bearings 22 of the trip bar 20 is a trip 23 having its lower end bifurcated as at 24 to receive the finger 20 15' so that a loose connection is formed between these two members through the medium of which the latch plate 13 is rocked on its pivot. Engaged in a notch 25 in the trip bar 20 is a wire 26 with which floating 25 objects are adapted to contact to move the bar 20 inwardly toward the section 11 of the fence post. When this bar 20 is moved inwardly against the tension of the coil spring 18 the trip is rocked away from the section 11 thus rocking the notch plate on its pivot and moving the plate so that its narrow longitudinal edge is moved in a direction toward the main section 11. When the parts have thus been moved the section 35 7 will be free to move laterally on the bolt to disengage the lugs 8 from the recesses 9 into section 7 and allow the main section and the parts carried thereby to assume a horizontal position as illustrated in 40 dotted lines in Fig. 2.

In order to allow the main section 11 to swing laterally when the part 20 is moved inwardly, a bifurcated beveled latch plate 27 is slidably engaged with the bolt 12 and has its upper end pivotally connected with a link 28 pivoted to the section 11 and having its free end engaged in an opening 29 in the trip 23 so that when this trip is actuated the latch plate 27 is moved to the position indicated in dotted lines in Fig. 1 to allow the joint between the section 5 and section 7 to become broken.

In some instances it is necessary to employ a gate and in this case the construction 55 of the post is modified, such a modified construction being illustrated in Figs. 4, 5 and 6 of the drawings. Referring to these figures a post of the gate is indicated at 29'. In order to latch the gate to the fence post 60 a chain 30 is engaged about the post and has one end attached to the section 11 permanently, while its opposite end is engageable with a pivoted latch 31 that is mounted upon the section 11 and is normally disposed in a vertical plane, a keeper

32 being provided which is pivoted adjacent the latch and engageable therewith. The keeper is longitudinally curved toward the trip bar 20 and has its free end disposed in the path of movement of this trip bar 70 so that when the trip bar moves inwardly the keeper is rocked on its pivot and disengaged from the latch to allow the same to drop and the chain disengaged therefrom.

This construction is merely illustrative 75 and it will be understood that the same may be modified and altered in many respects, and that my limits of modification are governed only by what is claimed.

What is claimed is:—

1. In a fence post, a rigid section adapted to be supported in the ground, a second post section which is connected with the rigid section, a main post section hingedly connected with the second section and capable of pivotal movement in a direction at right-angles to the second section, means for retaining all of the sections rigidly connected together, and means for rendering the first-mentioned means inoperative upon 90 a floating object contacting with the latter, and moving it.

2. In a fence post, a rigid section, a movable section hingedly connected with the rigid section, a main post section hingedly 95 connected with the hinged section and capable of movement at right-angles to the latter, slideable latch plates engaging the pivot joint of the sections and normally retaining the same against pivotal movement, 100 and a trip bar disposed forwardly of the main section and operatively connected with the latch plate whereupon a floating object contacting with the trip bar, the latch plates will be released to allow the pivot joint to 105 become broken.

3. In a fence post, a stationary section, a hinged section hingedly connected with the upper end of the stationary section, a main post section hingedly connected with 110 the upper end of the hinged section and capable of movement at right-angles to the latter, slideable latch plates engaging the hinged joints of the sections to retain the same in a vertical rigid position, a trip bar 115 hingedly connected with the main section extending forwardly of the same, an operative connection between the trip bar and the latch plates, and an expansible coil spring urging the trip bar forwardly to normally 120 retain the plates in locked position, the trip bar moving the plates to a position to allow the hinged joint to become broken upon the moving of the trip bar against the tension of the coil spring.

4. In a fence post, a stationary section, a section hingedly connected to the stationary section, a main section hingedly connected with the hinged section and movable at 125 right-angles thereto, latch plates engaging 130

- the hinged joint and normally retaining the sections in a rigid vertical position, a bar projecting from the main section, a trip bar hingedly connected with the main section and having an opening therein for the reception of a latch, means operatively connecting the trip bar and the latch plates whereupon the moving of the same in one direction the latch plates will be moved to
- 10 allow the sections to move on their pivot, and an expansible coil spring encircling the rod and urging the trip bar away from the main section.
5. In a fence post, a stationary section, a second section hingedly connected therewith, a main section hingedly connected with the second section and movable at right-angles thereto, latch plates engaging the hinged joint of the sections and normally retaining
- 15 the same rigidly connected together, a trip bar pivoted on the main section, a bifurcated trip carried thereby, a finger on one end of the latch plates engaging the bifurcated trip plate, a connection between the other
- 20 latch plate and the trip for actuation of the same, and a trip bar adapted to move, upon an object engaging therewith for actuating the trip to actuate the latch plates to allow the sections to move on their pivots.
- 25 6. In a fence post, a stationary section, lugs formed upon one face of the stationary section, a second section having recesses in one face thereover to interlock with the lugs, a pivot bolt passing through the two
- 30 sections, the second section being provided with a recess in its opposite end, a main post section, a lug formed upon the lower end
- 35 thereof and interlocked in the recess, a bolt passing through the upper end of the main section and the second section, a beveled plate slidably engaged upon the first-mentioned bolt and normally retained in position to prevent the second section from moving laterally with respect to the stationary section, a bifurcated latch plate slidably engaged with the second bolt and normally retaining the main section against pivotal movement, a trip bar extending forwardly of the main section and hinged thereto, a trip fixed to the trip bar and operatively connected with both the latch plates whereupon the moving of the trip bar in one direction the latch plates will be moved to a position to allow the lugs to ride out of the recesses to allow the sections to move on the bolt.
- 40 7. A fence structure including a stationary element and a movable element, means carried by the movable element, for holding the pivoted section and stationary section together, a latch operating mechanism independent of the means, for operating said means, to permit the movable element to swing downwardly, and means for returning said latch operating mechanism to its normal position.
- 45 8. In testimony that I claim the foregoing as my own, I have hereto affixed my signature in the presence of two witnesses.

LOGAN CORNELIUS.
